UNITED STATES PATENT OFFICE.

NELLIE M. BAILEY, OF KINSALE, VIRGINIA.

HOOK-AND-EYE FASTENING.

1,138,439.

Specification of Letters Patent.

Patented May 4, 1915.

Application filed November 3, 1914. Serial No. 870,136.

To all whom it may concern:

Be it known that I, NELLIE M. BAILEY, a citizen of the United States, residing at Kinsale, in the county of Westmoreland and State of Virginia, have invented certain new and useful Improvements in Hook-and-Eye Fastenings, of which the following is a specification.

This invention relates to hook and eye fastenings, and pertains especially to the class of hooks and eyes adapted to be attached without sewing and without separate or independent means of attachment.

The object of the invention is to provide in a hook and eye fastening, a hook portion composed of one piece of suitable wire, and an eye portion composed of a single piece of suitable wire, the wire of the respective portions being looped and twisted so as to form a closed end in each portion, an eye in one portion, an eye-engaging hook in the other portion, and a pair of resiliently engaging members in each portion.

A further object of the invention is to provide a hook and eye fastening of such simple, novel and peculiar construction as to afford a safety-pin fastening for the hook and for the eye, and so as to form a pair of coöperating spring arms in each portion of the fastening, one arm of each pair constituting a securing pin, and the other arm of each pair constituting respectively the hook and the eye members.

A still further object of the invention is to provide a hook and eye device which shall embody in each portion thereof a pair of resilient arms adapted to be hooked together in parallel position and parallel with the closing or meeting edges of a garment or other article to which the device may be applied for fastening said edges together.

Various other objects, advantages, and improved results are attainable in the practical application of the invention, as will be explained in the specification and set up in the appended claim.

In the accompanying drawings forming part of this application Figure 1 is a plan view showing the application of the invention. Fig. 2 is a perspective view of the hook portion of the fastening in position to be applied. Fig. 3 is a similar view of the eye portion with the arms in locked position.

The same reference characters denote the

same parts throughout the several views of the drawings.

With the exception of the formation of the hook and eye both portions of the fastening are of the same shape and construction, therefore the hook portion of the fastening will only be described in detail. A single piece of spring wire is folded upon itself to form a rigid end 1, one portion of the wire is looped around the other portion at 2, adjacent to the end 1, so as to form a pair of resilient arms having their fulcrum at the loop 2. One arm 3 of said pair of arms has a hook 4 formed central thereof by twisting the wire of this arm and folding it back upon itself, and the wire of the arm 3 terminates in an open catch-eye 5, for the end of the other or pin-arm 6. The pin-arm 6 is inserted through the material 7, adjacent to and parallel with the edges thereof, and the end or point of the arm is hooked into the catch-eye 5, whereby the device is securely pinned in proper position and safe against loosening or accidental displacement.

The eye portion of the fastening has a pin arm 8, and an arm 9 having an eye 10 formed central thereof for the hook 4, and this portion of the fastening is secured to the material 11, by inserting the pin arm therethrough adjacent to and parallel with the edge of the material opposite the hook portion of the fastening.

It will be observed that the arms are preferably made serpentine shape so that they mesh one with the other to hold the material therebetween more securely, that the fastening is secured parallel with the meeting edges of the material, and that upon releasing the pin arm and the hook and eye arms they will spring apart, whereupon the pin arms may be withdrawn and replaced as desired or as occasion may demand.

I do not wish to be understood as limiting the invention to any particular size, nor to the application of the fastening, and reserve to myself the right to make such changes therein in the manufacture thereof as may come within the scope of the appended claim.

Having thus described my invention what I claim as new and desire to secure by Letters Patent is:—

In a hook and eye fastening device, a hook member and an eye member each composed of a single piece of wire, the wire of each

2
member being folded centrally to form a pair of laterally diverging loops, serpentine arms looped together in a pair for each member and projecting from the lateral loops centrally between the latter and meshing throughout their length for clamping therebetween the material to which they are pinned, one of the arms of each pair terminating in a pin point, and the other arms having respectively a hook and an eye centrally thereof and terminating in an open

ring for catching the points therein, all of said arms adapted to swing parallel with the lateral loops in opening and closing movements. 15

In witness whereof I hereunto set my hand in the presence of two witnesses.

NELLIE M. BAILEY.
